EMMANUEL FELIX AUMONT, OF PARIS, FRANCE.

APPARATUS FOR THE MANUFACTURE OF OXYGEN.

1,088,052.

Specification of Letters Patent.

Patented Feb. 24, 1914.

Application filed May 16, 1911. Serial No. 627,639.

To all whom it may concern:

Be it known that I, EMMANUEL FELIX AUMONT, of 10 Rue Géricault, Paris, in the Republic of France, have invented certain new and useful Improvements in and Relating to Apparatus for the Manufacture of Oxygen, of which the following is a specification.

This invention relates to an apparatus for extracting the oxygen of the air by a liquefaction process.

An embodiment of the invention is illustrated by way of example in the accompanying drawing.

1 1 is a compressor forcing air into a collector 2 into which there opens a nest of tubes the central portion of which can be closed partially by means of the disk 3 controlled by a screw stem 4 for enabling the supply 15 to this central portion to be regulated at will. The nest of tubes enters two concentric compartments 9 and 12 separated by a jacket 13 where it acts as far as X Y as a temperature exchanger, the air becoming 20 cooled by means of the return oxygen and nitrogen of the apparatus as hereinafter explained. From X Y to the collector 5 it enters the compartments 11 and 10 which are also concentric where its lower part is 25 immersed in liquid oxygen; the air condensed under the influence of the temperature and of the pressure in producing a corresponding ebullition of external liquid oxygen. The liquid produced is collected 30 under pressure in the collector 5 and sent through the expansion cock 6, through a hydrogen liquefying apparatus 24, to the upper part of a rectification column 7. The expansion at the cock 6 produces a partial 35 evaporation of the liquid. The liquefying apparatus 24 serves to liquefy the gaseous portion resulting from this evaporation in such a manner that the whole of the air treated is discharged in liquid form at the 40 upper part of the rectification column 7 containing 21% of oxygen. Simultaneously by means of this supplementary liquefaction the additional quantity of cold units necessary for counter-balancing the inevitable 45 losses arising from imperfection in the exchanges and defective insulation are introduced into the air cycle. In the rectification column 7 the liquid falls from plate to plate 50 in becoming rich in oxygen; it reaches the expansion chamber 10 in the state of pure 55 liquid oxygen and is there vaporized partly in contact with the tubes of the central nest of tubes and partly in contact with the tubes of the peripheral nest. The passages 14 in the lower part of the jacket 13 establish communication between the compartments 11 and 10. The liquid oxygen admitted to compartment 11 is regulated by the cock 16 which restricts the outflow of the gaseous oxygen from the compartment 12 through 60 the conduit 17, thereby varying the gaseous tension in the compartment 12 and permitting the entrance of more or less liquid oxygen into the compartment 11. The gaseous oxygen contained in the annular compartment 10 ascends in the column 7 enriching the oxygen content in the descending liquid. However, the gases rich in nitrogen escape at the upper part of the column 7 through the conduit 8 and the chamber 9 which acts 65 as an exchanger, and issue at 15, cooling the gases in the compartments 12 and 13. 70

An auxiliary refrigerating machine furnishes the supplementary cold; it is constituted by a closed hydrogen cycle comprising a 75 compressor 26 delivering through the cooler C of any suitable type into a temperature exchanger 19 at the end of which an idiabatic expansion motor 23 is placed; its parts work dry without lubrication the exhaust 80 gases of the said motor circulating around the tubes of the liquefying apparatus 24 before returning around the nest of tubes of the temperature exchanger 19 where they are 85 again acted upon by the compressor 26. 90

Having now particularly described and ascertained the nature of my said invention and in what manner the same is to be performed I declare that what I claim is:

1. In apparatus for separating oxygen from air by liquefaction, means for liquefying the air, a rectification column for separating the liquid and gaseous constituents, and means arranged between the liquefying means and the rectification column for cooling 95 the liquefied air.
2. In apparatus for separating oxygen from air by liquefaction, means for liquefying air, and a hydrogen cycle for cooling the liquefied air comprising means for compressing and expanding the hydrogen. 100

3. In apparatus for separating oxygen from air by liquefaction, means for liquefying air, and a closed hydrogen cycle for cooling the liquefied air, comprising a compressor for compressing the hydrogen and an expansion engine wherein the compressed hydrogen expands.

In testimony whereof I have hereunto placed my hand at Paris (France) this fourth day of May, 1911.

EMMANUEL FELIX AUMONT.
In the presence of two witnesses:

H. C. COXE,
HENRY SCHWAB.
